UNITED STATES PATENT OFFICE.

FREDERICK E. ARROQUIER, OF WORCESTER, MASSACHUSETTS, ASSIGNOR TO WHITING-PATTERSON COMPANY, INC., A CORPORATION OF PENNSYLVANIA.

ENVELOPE MACHINE.

Application filed January 25, 1922. Serial No. 531,582.

To all whom it may concern:

Be it known that I, FREDERICK E. ARROQUIER, a citizen of the United States, and a resident of the city of Worcester, county 5 of Worcester, and State of Massachusetts, have invented certain new and useful Improvements in Envelope Machines, of which the following is a specification, reference being had to the accompanying drawings.

10 My invention relates to machines adapted for the production of what are commercially known as non-addressing or window envelopes, that is, envelopes having an opening in the face covered by a piece of transparent 15 or translucent paper through which the address on the contents of the envelope may be read.

A principal object of my invention is to provide in a machine adapted for the production 20 of envelopes of the character aforesaid, means whereby the piece of transparent or translucent paper, or patch as it is known in the art, will be positively and forcibly applied to the gummed envelope blank in 25 such manner and at such a point in the cycle of operations employed in the completion of the envelope as to insure its positive adherence to the blank without wrinkling or drawing so that in the completed envelope 30 the patch and the blank will be securely affixed together and the patch present a smooth and non-wrinkled appearance.

A further object of my invention is the provision in a machine for making window envelopes, of a creasing plunger of peculiar 35 construction and adapted for transferring an individual patch from a point above the level of the creasing table to a point adjacent the bottom of the folding box or trap, the 40 patch during its descent being maintained out of contact with the subjacent envelope blank preceding the plunger, and means to effectively and positively apply the patch to the blank as it rests upon the bottom of the 45 folding box preparatory to the retraction of the creasing plunger and the operation of the folding fingers.

A still further object of my invention is the provision in a machine of the character 50 aforesaid of improved means for cutting off the individual patches as needed from a continuous web of transparent or translucent paper, as well as means for ef-

fecting the transfer of the individual patches after they are formed by the cutting means to a point in proper vertical registration with the envelope blank as it rests beneath the creasing plunger prior to its descent through the creasing plate.

My invention further contemplates the enhancement of speed of operation of window envelope machines so as to enable a greater number of envelopes to be turned out in a given time than can be accomplished on the machines hitherto in use; the simplification of machines of this general type with a view to minimizing the time required for repairs and adjustments as well as an improved method of forming outlook envelopes.

My invention further includes all of the other various objects and novel features of construction and arrangement hereinafter more specifically described or claimed.

For the purpose of attaining the objects 75 of my invention I provide an ordinary reciprocating envelope machine of suitable construction with certain means and instrumentalities including means for intermittently feeding a continuous strip or web of 80 transparent or "glassine" paper, means for severing the web into predetermined lengths to form the individual patches, and means for transferring each individual patch to a 85 position in proper vertical registration with the gummed blank as it rests above the creasing plate, as well as with a peculiarly constructed creasing plunger adapted for supporting the patch in such position and embodying an auxiliary plunger and means for 90 effecting the actuation of said auxiliary plunger to forcibly press the patch upon the gummed blank as the same reaches the bottom of the folding box or trap and substantially simultaneously with the termination 95 of the downward stroke of the creasing plunger. While the said means may partake of various forms effective for accomplishing the desired functions, I will now, for the purpose of enabling those skilled in the art 100 to comprehend and practice the invention, describe in connection with the accompanying drawings a preferred embodiment of means suitable therefor and as applied to and in combination with an ordinary envelope machine of the reciprocating type

105

comprising means for supporting a stack of envelope blanks; means for gumming the blanks consecutively on the back and seal flaps and around the window opening; 5 means for consecutively feeding the gummed blanks to a position above a creasing plate; a vertically reciprocating creasing plunger rod, and means for folding the flaps of the gummed blanks to form completed envelopes, all of these operations and the means generally employed in machines of this character for effecting them being familiar to those skilled in the art. For the sake of simplicity, therefore, I have in the 10 accompanying drawings illustrated somewhat diagrammatically only those portions of the envelope machine requisite to a clear understanding of my invention.

In the said drawings accompanying and 15 forming part of this specification Fig. 1 is a side elevation of an envelope machine embodying my invention as aforesaid, certain parts being broken away for the sake of clearness and other parts being shown in 20 vertical section, and Fig. 2 is a similar view certain parts, however, being shown in different positions than in Fig. 1. Fig. 3 is a fragmentary enlarged vertical longitudinal section through the patch cutting and 25 transferring mechanism and adjacent parts; Fig. 4 is a similar view but with certain of the parts in a different position, and Fig. 5 is a front elevation of these parts in the position shown in Fig. 3. Fig. 6 is a fragmentary enlarged view partially in 30 vertical section of the creasing plunger rod actuating mechanism and adjacent parts; Fig. 7 a top plan view of the creasing plunger showing a patch in position therein, and Fig. 8 a further enlarged vertical section thereof on the line 8-8 in Fig. 7 looking in the direction of the arrows. Fig. 9 is a fragmentary top plan view of the patch cutting and transferring mechanism, 35 creasing plunger and adjacent parts; Figs. 10 and 11 enlarged detail views showing respectively in side and front elevation certain portions of the patch transferring mechanism, and Fig. 12 a view in front elevation of a preferred form of cutting knife removed from the machine. Like numerals are used to designate similar parts in the 40 several figures.

Referring now to the drawings the envelope machine shown therein comprises the usual frame 1 supporting a bed 2 adjacent the forward end of which (that is, toward the left hand side of the sheet in Figs. 1 and 2) is an elevator 3 serving to support a 45 stack of envelope blanks beneath the vertically reciprocating gumming dies 5 which are actuated by mechanism including a plunger 6 and suitable linkage and levers arranged to reciprocate it in the ordinary manner, the dies being arranged to descend

on the topmost blank of the stack and deposit a layer of gum upon the flaps thereof and around the window opening in the blank, it being of course understood that this opening has been formed in the blank 50 prior to its introduction into the machine. The mechanism also comprises a stripping plate 8 which serves to strip the blank from the dies as it is carried upward during the reverse stroke of the latter, and a reciprocating carriage 9 which serves to transfer the gummed blank from beneath the stripping plate to a creasing plate 10 beneath the vertically reciprocating creasing plunger 12, hereinafter more particularly described, 55 which operates to drive the blank downwardly through the creasing plate to the folding bed or trap 13 where the flaps are pressed and folded down into position by suitably actuated folding fingers 14 in the well known manner. Mechanism (not shown) is also usually provided for transferring the completed envelope from the trap to a suitable drier from which it is removed after a predetermined period of 60 time, all of these operations and the means ordinarily employed to effect them save the peculiarly constructed plunger utilized in my invention, being well known and thoroughly understood by those skilled in the 65 art.

For the adaptation of a reciprocating envelope machine of this general type to the production of window envelopes in accordance with my invention I provide and combine therewith various means and instrumentalities, a preferred embodiment of which will now be described.

Plunger mechanism.

The preferred form of creasing or main plunger which I employ and which is substituted for the plain rectangular plunger ordinarily utilized in reciprocating envelope machines, comprises a rectangular base 15 of proper size to force the envelope blank through the opening in the creasing plate and provided with a boss 16 for the reception of the lower end of the creasing plunger rod 17. This rod in the operation of the machine is reciprocated in any suitable manner, conveniently through linkage 18 as best shown in Fig. 6, a guide rod 19 on which slides a sleeve 20 connected with the plunger rod being preferably arranged to prevent disalignment of the latter through the angularity of the force exerted thereon by the linkage.

The base of the plunger is provided with a preferably rectangular opening 22 extending into the base from the rear edge thereof, which opening is slightly smaller than the size of the patch to be employed, so that the latter is capable of resting on the marginal edge of the opening which thus affords

- a convenient support therefor as best shown in Figs. 7 and 8 where the patch is designated as P. In vertically aligned relation with this opening is positioned an auxiliary 5 conveniently rectangular plunger 24 which is slightly smaller than the opening so as to afford suitable clearance between the walls thereof and the auxiliary plunger when the latter is depressed as hereinafter described. 10 and for resiliently supporting the auxiliary plunger from the main plunger the latter is preferably provided with a plurality, conveniently a pair, of laterally spaced arms 25 extending over and above the auxiliary 15 plunger through each of which loosely extends a stud 26 having its lower end secured to the plunger and its upper end provided with a head 27 between which and the upper surface of the arm is positioned a 20 spring 28 which thus normally sustains the weight of the auxiliary plunger. Means are also provided for effecting vertical movement of the auxiliary plunger with respect to the main plunger which may 25 conveniently comprise a lever 30 extending transversely of the main plunger and pivoted on a horizontal pivot stud 31 extending through a downwardly directed offset or third arm 32 integral with the 30 lever and a bifurcated lug 33 preferably formed integral with the main plunger. The longer arm of this lever, that is, the one which extends toward the rear of the machine, is preferably bifurcated at its end to receive the upper end of a post 35 which extends upwardly from the auxiliary plunger 35 preferably about the center thereof and which may also freely extend through a suitable opening in an arm 25' similar to the arms 25 which thus forms a guide for the post. The opposite or forward arm of the lever is adapted to engage on its under side with a headed spring-pressed stud 37 which passes vertically through a guiding 40 boss 38 formed integral with the plunger, a small coil spring 39 being seated within a cavity formed in this boss and beneath the head of the stud. The lower end of the stud 37 extends entirely through and normally projects below the under face of the main plunger, the several parts being so arranged 45 that sufficient pressure exerted on this projecting end of the stud is effective to rock the lever 30 on its pivot and depress the auxiliary plunger in opposition to the resistance of the springs 28. Furthermore, the length and adjustment of the several springs are preferably so gauged that the under surface of the auxiliary plunger will 50 normally substantially align with that portion of the upper surface of the base 15 which surrounds the aperture 22 as best shown in Fig. 8 while the under faces of the arms 25, 25' are sufficiently removed from the upper surface of the auxiliary plunger 55 to permit the latter to be lifted for a suitable distance above its normal position by depressing the forward end of the lever 30 for a purpose and in a manner to be hereinafter described. Preferably also, as hitherto stated, the substantially horizontal arms of the lever are of unequal length so that if the stud 37 be moved upwardly at a given speed to thereby elevate the adjacent arm of the lever, the post 35 and in turn the auxiliary 60 plunger will be depressed at a relatively greater speed by reason of their attachment to the longer arm of the lever. 70
- To enable certain portions of the transferring mechanism to pass beyond the front edge of the aperture 22 in the operation of bringing a patch beneath the auxiliary plunger, the main plunger is conveniently provided with a pair of laterally spaced slots 40 extending transversely therethrough for a sufficient distance to permit the transferring means to carry the patch to proper position without striking the main plunger. 75
- The function and operation of these several parts will hereinafter more fully appear in connection with the description of the operation of the machine. 80
- Patch cutting mechanism.*
- Suitable means are provided for severing individual patches as required from a web W drawn from a roll R of transparent or translucent paper which is supported on a horizontal shaft journaled in suitable brackets 45 extending rearwardly from the machine and secured to any convenient part thereof, for example and as shown to the transversely extending frame bar 1'. These brackets are laterally spaced apart sufficiently to accommodate the roll which is of width equal to the length of the patch to be used, and are laterally offset from the center line of the machine so that the web as drawn from the roll will be in alignment with that portion of the envelope blank, as it is fed beneath the creasing plunger, to which the patch is to be attached, a condition rendered necessary by the fact that the window opening in the ordinary window envelope is not in the center thereof but usually adjacent the lower left hand corner. 90
- The web is drawn downwardly and forwardly from the roll and arranged to pass under a horizontal guide roll 46 and thence between a pair of coacting feed rolls 47 and 48, journaled in the brackets, either or both rolls being preferably slightly corrugated in order to firmly grip the web. Means are provided for imparting an intermittent rotating motion to the feed rolls for the purpose of projecting the web forwardly at each actuation of the rolls for a distance equal to the width of the patch desired, and for this purpose I prefer to drive the roll 47 through the medium of a mutilated gear 50 suitably 95
- 100
- 105
- 110
- 115
- 120
- 125
- 130

actuated from a drive shaft 51 geared or otherwise connected to the main drive shaft of the machine in any suitable manner, not shown. In the form of the invention illustrated the gear 50 is provided with teeth extending about one-third of the way around its periphery, the rest of the face of the gear being blank while the pinion 52 carried by the shaft supporting the roll 47 is conveniently provided with three toothed segments and three short blank spaces therebetween as best shown in Figs. 3 and 4, so that when the constantly rotating gear 50 meshes with one of the toothed segments of the gear 52 the latter, and in turn the roll 47, will be rotated substantially one-third of a revolution after which the blank spaces on the two gears will come opposite each other and the roll be withheld from movement until the toothed section of pinion 50 engages the following toothed segment of gear 52. In this way for every complete revolution of the gear 50 the gear 52 and in turn the roll 47 will be rotated through substantially one-third of a revolution, and as the opposite end of the roll shaft is connected through a gear 54 with a pinion 55 on the shaft supporting the roll 48, the latter will partake of a corresponding movement thereby effecting a forward projection for a predetermined distance of the web which is gripped between the rolls. It will be obvious that the means just described constitute a simple and effective way of bringing about the forward projection of the web in predetermined lengths in properly timed relation with the speed of the main drive shaft of the machine.

As it is requisite, owing to the thinness of the patch paper employed, to effect a very fine adjustment between the rolls 47 and 48 in order to insure a positive feed of the web, I preferably provide means for adjusting the pressure between the rolls, conveniently by journaling the shaft of the lower roll 48 in boxes 57 which fit into and are vertically slidably in suitable ways 58 formed in the brackets, each box being supported on an L-shaped adjusting member 59 which rests between the under surface of the box and a cap 60 secured to the bracket. The portion of the member between the box and the bracket is very slightly tapered as best shown in Fig. 5 and the member adjustably secured in position by gib screws 61 one of which extends through the downwardly turned end of the member and into a threaded bore in the cap, and the others against its surface, so that by suitable manipulation of these screws the member may be forced inwardly to raise the box and in turn the roll or retracted to produce an opposite effect thus permitting very exact adjustment of the pressure between the rolls.

As the web is projected forwardly from

the rolls it passes onto a supporting table 65 carried by the brackets and provided with a transversely extending slot 66 open at its upper end and adapted to receive the vertically reciprocating cutting knife 67 which is effective to cut off the patch from the web. Preferably this knife, which is formed of thin tempered metal, comprises a cutting edge 68, beveled upwardly and outwardly in opposite directions from its center as best shown in Fig. 12 and a substantially rectangular upper portion provided with eyes 69 for the attachment of lifting springs 70 hereinafter described. I have found that a knife comprising a cutting edge of the character described is particularly well adapted for severing the peculiar paper used in the formation of the patches since in its descent thereon it first contacts with the paper at the center and then simultaneously cuts outwardly in opposite directions with a shearing effect whereby the pressure on the paper is equalized and any tendency toward disalignment of the web which might occur if the paper were cut from one edge to the other with an ordinary knife of the guillotine type is avoided.

The knife is of course of sufficient width to entirely sever the web from edge to edge and is preferably supported between a pair of plates 71, 72, the extreme lateral edges being engaged in suitable vertically positioned guides 73 the upper ends of which are secured to a transverse member 74 carried by the bracket and the lower ends suitably spaced above the table 65.

Suitable means are provided for actuating the knife and the plates which may preferably comprise a vertically extending post 75 secured at its lower end to the upper part of the knife and passing freely upwardly through the transverse member 74, a collar 76 carried by the post limiting its upward movement by contact with the member. Above the member the post is provided with a head 77 which is cooperative with a finger 78 extending from a boss 79 rotatably carried by a transversely extending shaft 80 which is journaled in the brackets 45. This boss is also provided with a rearwardly extending arm 82 carrying a cam roller 83 at its extremity which is operative to engage a cam 84 rigidly secured on the shaft 51 and rotatable therewith. Preferably I arrange means for loosely holding the end of the finger 78 adjacent the head 77 conveniently by providing a suitable aperture 85 in the end of the finger adapted to loosely receive a headed screw 86 extending downwardly into the head so that on an upward movement of the finger the latter will be effective to lift the post and in turn the knife and upon a downward movement to depress the same. A spring 87 is preferably conveniently arranged as by attachment of its upper

end to a bracket 88 carried by the frame of the machine and at its lower end to the finger 78 to cause the cam roller 83 to follow the cam 84, which latter is of such shape 5 as to oscillate the boss 79 at a proper time in the cycle of operations of the machine so as to depress or retract the knife.

To afford means whereby relative vertical movement may take place when required between the plates 71 and 72 moving unitarily and the knife, I preferably provide the former with upwardly extending arms 90 which are turned inwardly and arranged to support the upper ends of the springs 70, the lower ends of which are secured in the eyes 69 of the knife, the plates being suitably secured together conveniently by rivets 91 so placed as to limit the possible relative upward movement of the blade with respect to the plates, it being of course understood that whatever be the means employed for securing the plates together the same will be of such construction as to maintain the plates in relatively spaced relation 20 to permit the knife to readily slide therebetween.

With the several parts constructed as described it will be apparent that when the post is depressed by the action of the finger, the plates and knife will together initially move downward until the plates contact on opposite sides of the slot 66 with the surface of the web resting on the table 65 thereby arresting their further progress and holding the web firmly while the knife is free to enter the slot and complete its full downward stroke to sever the patch. Conversely on the upward movement of the finger from its lowermost position the knife 40 is withdrawn first from the slot and the plates then lifted from the table entirely clear of the forward edge of the web adjacent the rear side of the knife and of the patch which has been severed from the web and rests on the table. Instead of arranging the lower edge of plate 72 to contact directly with the web, I may in the preferred construction and as shown, provide the table with a plurality of depressions 50 93 adjacent the rear face of the knife in which are secured small flat springs 94 arranged so their free ends will normally project slightly above the surface of the table as shown in Fig. 4, and I may secure to the rear face of the plate a plurality of spaced substantially L-shaped feet 95 preferably one above each of these springs so that when the plates are elevated as shown in Fig. 4 the springs and feet form a substantially V-shaped passage for the entrance of the web, the springs on the descent of the plates being depressed by the feet from their normal position to that shown in Fig. 3. The arrangement of these parts in the manner described I have found assists in

guiding the web and facilitates its smooth and even forward travel as well as insuring a firm pressure thereon during the cutting operation.

Patch transferring means.

For the purpose of transferring the severed patch from its position on the table 65 to a point beneath the auxiliary plunger 24, suitable means arranged to grip the patch while on the table and carry it forward to the desired point are provided and while said means may be of any suitable construction I prefer to use substantially the form of mechanism now to be described.

I therefore preferably provide a pair of forwardly extending, laterally spaced ways 100 rigidly supported, conveniently from the brackets 45, and in which a transversely extending carrier plate 101 is arranged to horizontally reciprocate. For effecting this movement of the plate I prefer to secure to a bifurcated lug 102 formed thereon, an offset rearwardly extending link 104 the rearmost extremity of which is pivoted to a downwardly and forwardly curved arm 105 integral with a boss 106 pinned or otherwise secured to the shaft 80 so as to turn therewith, and I arrange means for effecting the oscillation of the shaft at suitable times in the cycle of operation, conveniently by means of a crank 107 carrying a cam roll 108 cooperative with the surface of a suitable cam 109 rotated by the shaft 51. A spring 110 is arranged in some convenient way so as to cause the cam roll to at all times follow the face of the cam, preferably by securing one end of the spring to an arm 111 projecting radially upward from the shaft and the other end of the spring 95 to a suitable point on one of the brackets. Under these conditions it will be obvious that a reciprocating motion will be imparted to the carrier plate sufficiently great to carry it from a point substantially over the table 100 65 to a point substantially over the auxiliary plunger.

The carrier plate 101 is employed to support suitable grippers, best shown in Figs. 10 and 11, which are operative to seize the forward edge of the patch and drag it to the desired position beneath the creasing plunger when the plate moves forward. One of these grippers is preferably placed adjacent each of the ends of the plate and as they are entirely similar save for the modification obviously necessary to enable them to work adjacent opposite ends of the plate a description of one of them, for example, that on the right hand side of the machine when viewed as in Fig. 5, will suffice for both. Each gripper comprises a downwardly projecting plate 115 having its upper end turned over the surface of the carrier plate 101 and secured thereto by 110 115 120 125 130

suitable screws. The lower part 116 of the plate is cut away on its inner side so as to decrease its width and the extremity thereof directed horizontally rearwardly thus providing a toe 117, and secured to the forward face of the upper part of the plate, as by a screw 118, is a forwardly projecting lug 119 to which is pivoted, by a horizontally extending pivot screw 120, a rearwardly and downwardly curved claw 121 having an L-shaped end 122 co-operative with the rear end of the toe 117. The claw is preferably formed integrally with the inner end of a sleeve 123 which is rotatably supported on the stationary pivot screw between the head thereof and the face of the lug 119, and preferably formed integrally with the outer end of the sleeve is a bell crank lever 124, the lower arm of which carries a laterally projecting elongated trip roll 125 and the upper arm a short cam roll 126, a spring 128 being coiled about the head of the pivot screw and arranged so as to continually force the claw downwardly to bring the L thereof into engagement with the toe 117.

Also pivotally supported on the lug 119 and above the roll 126 is a rearwardly projecting finger 130 which is constantly urged downwardly through a spring 131 interposed between the finger and a convenient portion of the lug, this finger adjacent its pivot being provided with a suitable cam notch 132 adapted to receive the roll 126 under certain conditions of operation.

Near the forward end of the adjacent way 100 is a downwardly depending post 135 provided at its lower extremity with an inwardly directed trip 136 having a curved cam surface 137 arranged in the path of the trip roll 125 in such manner that as the carrier plate nears the end of its forward movement the roll will engage the cam surface and be lifted upwardly to in turn lift the claw away from the toe 117 and engage the roll 126 in the cam slot 132. This slot is so shaped as to thereafter retain the roll therein to maintain the claw in elevated position (see Fig. 4) until the rear end of the finger is lifted, conveniently by contact with an inwardly projecting trip 138 carried by a lug 139 rigidly secured as by screws 140 to the under side of the adjacent way 100 toward the rear end thereof.

To form a guide for the patch as it is drawn from the table 65 I may, if desired, provide the latter with an angularly upwardly directed lip 142 and a plurality of spring fingers 143 positioned thereabove which are so adjusted as to lightly touch the patch and assist in its being drawn smoothly from the table by the grippers, while to permit the carrier plate to move forward sufficiently without coming in contact with the creasing plunger rod 17 or the

boss 16 I preferably cut the same away as at 145 to afford the necessary clearance.

Operation.

It will be understood that in the operation of an envelope machine embodying means and instrumentalities in substantially the form hereinbefore described, a stack of envelope blanks of proper shape and having the window openings cut therein are supported on the elevator 3 with the surface which is to form the inside of the envelope, upward. The gumming dies descend consecutively on the uppermost blank which is thus gummed around the window opening and the flaps and raised on the upward stroke of the die to the stripping plate 8 from whence it is conveyed rearwardly by the conveyer 9 to proper position on the creasing plate 10 beneath the creasing plunger 12, the movement of which is so timed as to bring it above the plate when the envelope is moved thereon.

While these several operations have been in progress and preferably about the time that the gumming operation takes place, the web W of glassine paper drawn from the roll R has been projected forwardly onto the table 65 through the intermittent action of the rolls 47 and 48, the relative position of the blanks and teeth on the mutilated gears 50 and 52 being such that after the movement of the feed rolls ceases, the cam 84 becomes effective to depress the knife and adjacent plates 71, 72, the latter serving to steady the web while the knife severs the patch.

Substantially simultaneously with the severance of the patch the carrier plate 101 supporting the grippers has moved rearwardly with the claw 121 in elevated position (as in Fig. 4) until contact of the finger 130 with the trip 138 raises the trip to release roll 126 and allow the L-shaped end of the claw to descend on the forward end of the patch projecting slightly over the front edge of the table 65 and under which the rear end of the toe 117 has passed. Thus the forward edge of the patch is gripped securely between the claw and toe of one of the grippers adjacent each of the side edges of the patch.

The carrier plate now begins its reverse or forward movement, which is preferably substantially contemporaneous with the rearward movement of the envelope blank, in its traverse from gumming position to the creasing plate, while the creasing plunger rod meanwhile continues its upward movement and approaches the limit of its up stroke. Previously, however, to that limit being reached, the forwardly projecting end of the lever 30 carried by the main plunger is brought into engagement with a suitable, preferably adjustable stop, conveniently in the form of a stop screw 150 carried by a bracket 151 secured to the frame of the ma-

chine. This stop is operative to slightly depress the said end of the lever to thereby elevate the other end and in turn the auxiliary plunger 24 slightly above its normal position (see Fig. 1) so that when the plunger rod reaches the limit of its upward movement thus bringing the marginal edge of the opening 22 of the main plunger substantially into the plane of the forwardly moving patch, the latter can be drawn over said opening and beneath the auxiliary plunger, the depending portion of the grippers passing ends of the latter and into the slots 40 in the main plunger. As the carrier plate 101 approaches the end of its forward travel, the trip roll 125 through contact with the cam surface 137 is raised to lift the claw from the patch just as the carrier attains the end of its movement and at the same time the roll 126 enters the cam slot 132 which permits the finger 130 to descend from its raised position and lock the roll in the slot to hold the claw in elevated position during the return or rearward stroke of the carrier plate as already described.

The creasing plunger 101 now begins its downward movement and as the pressure on the forward end of the lever 30 is gradually released the auxiliary plunger 24 descends until it contacts or substantially contacts with the upper surface of the patch horizontally supported on the marginal edges of the aperture 22 and out of contact with the subjacent blank, in which position the patch and auxiliary plunger remain during the major portion of the descent of the main plunger which is effective in the usual manner to force the blank through the creasing plate to turn the flaps vertically upward and to carry the blank in that condition downwardly into the folding box.

As the main plunger nears the limit of its downward movement the projecting end of the stud 37 contacts through the envelope with the trap 13 forming the bottom of the folding box and is thus moved upwardly relatively to the downwardly descending main plunger to actuate lever 30 and depress the auxiliary plunger relatively downward with respect to the main plunger, and, owing to the dissimilarity in length of the horizontal arms of the lever 30, at a relatively greater speed, so that the auxiliary plunger becomes effective, substantially simultaneously with the ending of the down stroke of the main plunger, to positively and forcibly press the patch, which has meanwhile been carried down in front of the auxiliary plunger through the aperture 22, to the gummed surface of the blank adjacent the window opening.

The reverse or upward movement of the plunger rod now being initiated, the main plunger, carrying the auxiliary plunger, is lifted clear of the folding fingers 14, the

auxiliary plunger under the influence of its supporting springs returning to normal position as the main plunger rises and relieves the pressure on the stud 37. The folding fingers are then operated in the ordinary manner to fold and press the flaps into place thus completing the envelope which is ejected from the folding box by a downward movement of the trap and generally transferred to drying mechanism (not shown). The cycle of operation so far as one envelope blank and its corresponding patch are concerned having now been completed, the creasing plunger rises until it clears the creasing plate after which another blank is brought into position thereover and a new cycle initiated.

It will be observed that during the operation of the machine the individual patch is supported in spaced relation but proper vertical aligned registration with the envelope blank from the time when the creasing plunger begins to descend until the blank has been carried down into the folding box and the creasing plunger has substantially completed its downward stroke, at which time the patch is positively applied to the blank through the action of the auxiliary plunger. The maintenance of the patch out of contact with the blank and application thereof thereto at the completion of the creasing operation I believe to be broadly new, and I therefore do not intend to confine myself to any particular means for accomplishing that result, although in practice I have found the means herein illustrated and described are well adapted therefor.

Moreover, while I have herein illustrated and described with considerable particularity a preferred embodiment of my invention as embodied in an organized envelope machine, I do not thereby in any way desire or intend to limit myself to any specific construction or arrangement of parts, as means and instrumentalities other than those to which I have referred may, under certain conditions, be utilized if desired for accomplishing the various functions and operations and likewise, suitable modifications may be made in the design, construction and details of arrangement of the various elements which I have illustrated and described as employed in my said preferred embodiment without in any way departing from the spirit and scope of the invention as defined in the appended claims.

Having thus described my invention, I claim and desire to protect by Letters Patent of the United States:

1. A machine for making window envelopes comprising means for supporting an envelope blank, means for gumming the blank on the back and seal flaps and around the window opening therein, a creasing plunger, means for feeding the gummed

blank to a position beneath the plunger, means for intermittently feeding a web of paper toward the creasing plunger, means for severing the web to form an individual patch, means for transferring said patch to a position above and in vertical alignment with the blank as it rests beneath the plunger, and means carried by the plunger for positively applying the patch to the blank substantially concurrently with the termination of the down stroke of the plunger.

2. A machine for making window envelopes comprising means for supporting an envelope blank, means for gumming the blank on the back and seal flaps and around the window opening therein, a creasing plunger, means for feeding the gummed blank to a position beneath the plunger, means for intermittently feeding a web of paper in a direction opposite to the travel of said blank from the gumming means, means for severing the web to form an individual patch, means for transferring said patch to a position above, out of contact and in vertical alignment with the blank as it rests beneath the creasing plunger, and means comprising an auxiliary plunger carried by the creasing plunger for applying the patch to the blank substantially concurrently with the termination of the down stroke of the creasing plunger.

3. A machine for making window envelopes comprising means for supporting an envelope blank, means for gumming the blank on the back and seal flaps and around the window opening therein, a creasing plunger, means for feeding the gummed blank to a position beneath the plunger, a folding box beneath said plunger, means for intermittently feeding a web of paper toward the creasing plunger in a direction opposite to the travel of said blank from the gumming means, means for severing the web to form a patch, means for transferring said patch to a position spaced from, above and in vertical alignment with the blank as it rests beneath the creasing plunger, and means carried by and relatively movable with respect to the creasing plunger for positively applying the patch to the blank as the latter rests on the bottom of the folding box.

4. A machine for making window envelopes comprising a vertically reciprocatory creasing plunger, means for moving a gummed envelope blank beneath said plunger, means for transferring a patch to a point above the blank as it rests beneath the plunger, and positively operated means carried by the plunger for applying the patch to the blank substantially contemporaneously with the termination of the down stroke of the plunger.

5. A machine for making window envelopes comprising a vertically reciprocatory creasing plunger, means for moving a gummed envelope blank beneath said plunger, a folding box into which said plunger is adapted to carry said blank, means for feeding a web of paper toward the plunger, means for severing said web to form an individual patch, means for transferring said patch to the creasing plunger when above the envelope blank, means for supporting said patch out of contact with the blank during the major portion of the descent of the plunger, and positively operated means for applying the patch to the blank as the latter rests on the bottom of the folding box.

6. A machine for making window envelopes comprising a vertically reciprocatory creasing plunger, means for moving a gummed envelope blank beneath said plunger, a folding box into which said plunger is adapted to carry said blank, means for transferring an individual patch to said creasing plunger while the latter is above the blank, means for supporting said patch out of contact with the blank during the major portion of the descent of the plunger, and means comprising an auxiliary plunger carried by the creasing plunger adapted to positively apply the patch to the blank as the latter rests on the bottom of the folding box.

7. A machine for making window envelopes comprising a vertically reciprocatory creasing plunger, means for moving a gummed envelope blank beneath said plunger, a folding box into which said plunger is adapted to carry said blank, means for forming an individual patch from a web of patch paper, means for transferring said patch in a direction opposite to the travel of said blank as it is moved to beneath the creasing plunger to a position above and out of contact with the blank, means for maintaining the patch in such position during the major portion of the descent of the creasing plunger, and positively operated means for moving said patch downwardly relative to the creasing plunger and applying it to the blank as the latter rests on the bottom of the folding box.

8. A machine for making window envelopes comprising a vertically reciprocatory creasing plunger, means for moving a gummed envelope blank beneath said plunger, means for forming an individual patch from a web of patch paper, means for transferring said patch to the creasing plunger while the latter is above the blank, means for supporting the patch out of contact with the blank during the major portion of its descent, and means carried by the creasing plunger for bringing the patch into contact with the blank substantially simultaneously with the termination of the down stroke of the plunger.

9. In a machine for making window envelopes, the combination of a reciprocatory creasing plunger, means for transferring an envelope blank to a position therebeneath, means for transferring a patch to the plunger above the blank, and means carried by the plunger for applying the patch to the blank substantially simultaneously with the termination of the stroke of the plunger in one direction. 10
10. A machine for making window envelopes comprising a reciprocatory creasing plunger having an opening, an auxiliary plunger carried by the creasing plunger and supported in alignment with the opening, means for transferring a gummed envelope blank to a point adjacent the creasing plunger, means for transferring an individual patch to the creasing plunger and aligned with the opening, and means for moving the auxiliary plunger through the opening to apply the patch to the blank substantially contemporaneously with the termination of the creasing stroke of the creasing plunger. 15
11. A machine for making window envelopes comprising a vertically reciprocatory creasing plunger having an opening, an auxiliary plunger carried by the creasing plunger, means for normally supporting the auxiliary plunger with its lower surface in substantial alignment with the upper edge of the opening, means for transferring a gummed envelope blank to a point beneath the creasing plunger, means for transferring an individual patch to the creasing plunger above the opening, means for lifting said auxiliary plunger away from said opening to permit the patch to be positioned thereover by the transferring means, and means for positively moving said auxiliary plunger downwardly with respect to the creasing plunger to carry the patch through the opening and against the blank substantially contemporaneously with the termination of the down stroke of the creasing plunger. 20
12. In a machine for making window envelopes, a creasing plunger having an opening, an auxiliary plunger carried by the creasing plunger and aligned with said opening, yielding means supporting said auxiliary plunger, and means for moving the auxiliary plunger into the opening against the resistance of said yielding means. 25
13. In a machine for making window envelopes, a creasing plunger having an opening, an auxiliary plunger carried by the creasing plunger and yieldingly supported in alignment with said opening, and means comprising a lever extending transversely of said creasing plunger cooperative at one end with the auxiliary plunger and at the other end with a movable stud extending below the lower face of the creasing plunger for moving said auxiliary plunger into said opening when said stud is actuated. 30
14. In a machine for making window envelopes, the combination of a reciprocatory creasing plunger having an opening, an auxiliary plunger mounted on the creasing plunger and aligned with said opening, means for normally supporting said auxiliary plunger above the opening during the major portion of the down-stroke of the creasing plunger, and means operative to raise the auxiliary plunger with respect to the creasing plunger as the latter approaches the end of its up-stroke. 35
15. In a machine for making window envelopes, the combination of a vertically reciprocatory creasing plunger, an auxiliary plunger carried by said creasing plunger, means for yieldingly supporting said auxiliary plunger above the lower face of the creasing plunger during the major portion of the down stroke of the latter, means for raising said auxiliary plunger with respect to said creasing plunger as the latter approaches the end of its up-stroke, and means for depressing said auxiliary plunger with respect to said creasing plunger as the latter nears the end of its down stroke. 40
16. In a machine for making window envelopes, the combination of a reciprocatory creasing plunger, an auxiliary plunger carried thereby, means for yieldingly supporting said auxiliary plunger from the main plunger, and means for effecting relative movement of said auxiliary plunger with respect to said creasing plunger at a predetermined point in the stroke of the latter. 45
17. In a machine for making window envelopes, the combination of a vertically reciprocatory creasing plunger, an auxiliary plunger carried thereby, means for normally supporting said auxiliary plunger in stationary relation with said creasing plunger, and means for imparting to the auxiliary plunger a relatively rapid downward movement with respect to the creasing plunger as the latter approaches the end of its down stroke. 50
18. In a machine for making window envelopes, the combination of a vertically reciprocatory creasing plunger, an auxiliary plunger carried thereby, means for normally supporting the auxiliary plunger in stationary relation with the creasing plunger, means for imparting to the auxiliary plunger a relatively rapid downward movement with respect to the creasing plunger as the latter approaches the end of its down stroke, and means for imparting to the auxiliary plunger a relatively rapid upward movement with respect to the creasing plunger as the latter approaches the end of its up-stroke. 55
19. The method of forming a window envelope which comprises the steps of gum- 60

- ming an envelope blank, bending the flaps of the blank to a position substantially at right angles to the body thereof, bringing the blank to a supporting surface, positively 5 applying the patch to the blank while the latter is supported on such surface, and thereafter folding the flaps of the blank substantially parallel with the face thereof to form the completed envelope.
- 10 20. The method of forming a window envelope blank which comprises the consecutive steps of suitably gumming an envelope blank, bending the flaps of the blank to a position normal to the body thereof while 15 maintaining an individual patch in alignment with but spaced from the window opening in the blank, moving the blank to a supporting surface, applying the patch to the blank substantially as the latter reaches 20 such surface and folding the flaps of the blank substantially parallel with the face thereof to form the completed envelope.
21. The method of forming a window envelope which comprises the steps of suitably 25 gumming an envelope blank having a window opening therein, bending the flaps of the blank to a position substantially at right angles to the body thereof while maintaining an individual patch in alignment with 30 but spaced from the window opening, bringing the blank to a supporting surface, positively applying the patch to the blank while the latter is supported on such surface, and then folding the flaps of the blank substantially 35 parallel with the face thereof to form the completed envelope.
22. The method of forming a window envelope which comprises the steps of gumming a window envelope blank on the back 40 and seal flaps and around the window opening, forming an individual patch, bringing the patch into alignment with the opening but spaced from the blank, bending the flaps substantially normal to the body of the blank while 45 maintaining the patch spaced therefrom, bringing the blank to a supporting surface, positively applying the patch to the blank while supported on said surface, and then folding the back and end 50 flaps of the blank substantially parallel to the face thereof to form the completed envelope.
23. The method of forming a window envelop which comprises gumming a window
- envelope blank on the back and seal flaps 55 and around the window opening, forming a patch adapted to cover the window opening from a continuous strip of patch paper, moving said patch and said blank in opposite directions until the patch is in vertical 60 alignment with the window in the blank, bending the flaps of the blank substantially normal to the body thereof and moving the blank to a supporting surface while maintaining the patch out of contact with the 65 blank, positively applying the patch to the blank to cover the window opening, and folding the flaps of the blank substantially parallel with the front thereof to form a 70 completed envelope.
24. The method of forming a window envelope which comprises supporting adjacent a creasing station in an envelope machine a window envelope blank having a coating of gum adjacent the window opening 75 therein, bringing a patch into aligned but spaced relation with said opening and said gummed surface, moving the blank and the patch from the creasing station while maintaining said relation between the blank 80 and the patch and simultaneously bending the flaps of the blank substantially normal to its body portion, bringing the blank to rest, then positively applying the patch to the gummed surface so as to cover the window opening, and thereafter folding said 85 flaps substantially parallel with the body of the blank so as to form a completed envelope.
25. The method of forming a window envelope 90 which comprises gumming a window envelope on the back and seal flaps and around the window opening, bringing a patch into alignment with the opening but spaced from the blank, bending the flaps substantially normal to the body of the blank, bringing the blank to a supporting surface while maintaining the patch spaced from the blank, applying the patch to the blank 95 to cover the window opening while the blank is supported on said surface and then folding the back and end flaps of the blank substantially parallel to the face thereof so as to form the completed envelope.
- In witness whereof, I have hereunto set 105 my hand this 23rd day of January, 1922.

FREDERICK E. ARROUQUIER.
